Primary Examiner — Mark Goodwin(74) *Attorney, Agent, or Firm* — Norton Rose Fulbright Canada LLP; Alexandre Daoust(57) **CLAIM**

The ornamental design for a sap collector, as shown and described.

DESCRIPTION

FIG. 1 is an oblique view of a sap collector showing my new design;

FIG. 2 is a rear view thereof,

FIG. 3 is a top view thereof,

FIG. 4 is a right side view thereof,

FIG. 5 is a left side view thereof,

FIG. 6 is a front view thereof, and,

FIG. 7 is a bottom view thereof.

The dashed line showing of structural lines is included for the purpose of illustrating non-claimed subject matter and forms no part of the claimed design.
